UNITED STATES PATENT OFFICE.

WILLIAM T. TANKING, JR., OF RACINE, WISCONSIN.

SUPPORT.

1,393,052.

Specification of Letters Patent. Patented Oct. 11, 1921.

Application filed August 5, 1919. Serial No. 315,407.

To all whom it may concern:

Be it known that I, WILLIAM T. TANKING, Jr., a citizen of the United States, and resident of Racine, in the county of Racine 5 and State of Wisconsin, have invented new and useful Improvements in Supports, of which the following is a description, reference being had to the accompanying drawings, which are a part of this specification.

10 The present invention relates to certain new and useful improvements in supports, and has for one of its objects to provide a support adapted for use in connection with tables, stands, "Christmas" trees or the like, 15 which will be capable of ready attachment or detachment.

Another object of this invention is to provide a support for the purposes stated which will be capable of being folded when not 20 in use to occupy a small amount of space.

25 A further object of this invention is to provide a device of the class described in which the supporting legs have means moved to impinge against the member being supported by the weight of said member, and in which the supporting platform is formed from a single sheet of material so constructed as to readily support a weight placed thereon.

30 With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

40 In the accompanying drawing, I have illustrated one complete example of the herein disclosed invention constructed according to the best mode I have so far devised for the practical application of the 45 principles thereof, and in which:

Figure 1 is a top plan view of my support.

Fig. 2 is a side plan view thereof.

Fig. 3 is an enlarged perspective view of 50 one corner of the supporting base or platform, and a portion of the supporting leg pivoted therein.

Fig. 4 is a sectional view of a portion of the member being supported and the supporting platform illustrating the novel 55 means carried by the member being sup-

ported and engaged with an aperture in the supporting platform, and

Fig. 5 is a sectional view through the supporting platform taken on the line 5—5 60 of Fig. 1, said view illustrating a slightly modified form of platform.

Referring now more particularly to the accompanying drawing, 6 designates a supporting base or platform which is of substantially triangular shape having each corner thereof squared as at 7 and provided with a central aperture 8 formed by striking the opposed pair of spaced ears 9 from the platform as best shown in Fig. 3. 65

The member to be supported designated as at 10 has secured to its lower end a stud member 11 which has its outer portion provided with a head 12 and a flared shank or intermediate portion 13, the head 12 being 70 engaged through a central aperture 14 formed in the platform 6 as best shown in Fig. 4. The head 12 is of a size as to just permit the passage through the aperture 14 and has its lower end slightly rounded as 75 at 12' for convenience in guiding the same through said aperture.

Pivotedly secured in each recess 8 by means of a bolt 15 is a supporting leg 16 having its upper end disposed above the 80 platform 6 and provided with teeth 17. As best shown in Fig. 3, the supporting legs 16 are formed of channeled material and the bolt 16 passes centrally through the adjacent pair of ears 9 and the side walls 90 of the adjacent supporting leg. To secure the pole, or other member to be supported, upon the platform 6, the stud 11 is first driven in the lower end thereof and then the same is positioned on the platform with the stud passing through the central aperture 14 as best shown in Figs. 2 and 4, when the supporting legs 16 are moved on their pivots to bring their upper ends, carrying the teeth 17, into engagement with the pole 100 10, the weight of which will cause the teeth 17 to bite into the pole as will be readily apparent from Fig. 2.

In the modified form of platform 6 depicted in Fig. 5, the side edges thereof are 105 laterally flanged as at 6' to give added strength to the same as will be at once apparent.

While I have illustrated my invention as being adapted for use in connection with 110 pole or tree members 10, it would be at once apparent that its uses are varied in that the

same may be used to support a broken table leg, and in fact, for any other purpose.

What I claim as my invention is:

1. A support of the class described, comprising a substantially triangular platform formed of sheet metal and provided with a central aperture and a notched recess at each corner, a pair of spaced ears struck from said platform at each recess, a sheet metal supporting leg disposed in each recess having pivotal engagement with the adjacent pair of ears, said supporting legs being extended upwardly beyond their pivots, a centering pin adapted to be partially driven longitudinally into the base of the member being supported before said member is positioned on said support, the projecting end of said pin being adapted to slip into said aperture, prongs formed on the upper ends of each of said supporting legs and adapted to engage the member being supported whereby said pin may be driven into the base of said member and said member then positioned in said support with said pin projecting through said aperture and the prongs in engagement with the sides of said member, the weight of said member causing said prongs to effectively bite thereinto.

2. A support of the class described, com-

prising a substantially triangular platform formed of sheet metal and provided with a central aperture and a notched recess at each corner, a pair of spaced ears struck from said platform at each recess, a sheet metal supporting leg disposed in each recess having pivotal engagement with the adjacent pair of ears, said supporting legs being extended upwardly beyond their pivots, a centering pin adapted to be partially driven longitudinally into the base of the member being supported before said member is positioned on said support, the projecting end of said pin being adapted to slip into said aperture, prongs formed on the upper ends of each of said supporting legs and adapted to engage the member being supported whereby said pin may be driven into the base of said member and said member then positioned in said support with said pin projecting through said aperture and the prongs in engagement with the sides of said member, the weight of said member causing said prongs to effectively bite thereinto, and a depending reinforcing flange formed on the side edges of said platform.

In testimony whereof, I affix my signature.

WM. T. TANKING, JR.
